UNITED STATES PATENT OFFICE

SAMUEL N. SAGER, OF CHICAGO, ILLINOIS

PULL-OFF LEGGING

Application filed October 23, 1930. Serial No. 490,572.

This invention relates in general to a legging which may be quickly removed and has more particular reference to a pull-off legging used by workmen in foundries, machine 5 shops, and the like.

One of the principal objects of the invention is in the provision of a protected top adjustment by means of which this portion of the legging may be varied in size.

10 A further object of the invention is in the provision of a covering flap which protects the top adjustment from the engagement and lodging of sparks or pieces of molten metal which might fuse the metal fastening parts if they become lodged in contact therewith.

15 A further object of the invention is to protect the top fastening against accidental contact or disengagement of the parts of the legging.

20 A still further object of the invention is in the provision of a protecting flap which does not interfere with the quick removal of the legging.

25 Other objects of the invention will appear hereinafter, the drawing illustrating a preferred form of the invention.

In the drawing, Fig. 1 is a view of the legging folded as if applied to the leg of a 30 wearer;

Fig. 2 is a detail view of the upper fastening portion of the legging with the protecting flap raised; and

Fig. 3 is a part sectional view as taken on the line 3—3 of Fig. 1, omitting the flap.

35 This legging is intended to be worn in foundries, machine shops, and the like, and if sparks or molten metal should happen to strike and lodge upon the metal attachment parts of the legging there is a possibility that the parts might become fused together so that in attempting to remove the legging to protect the wearer from burning, the legging would not become unfastened and could not 40 be quickly removed, so that a serious burn might result.

The present invention will prevent such an accident by covering the exposed fastening means and by preventing the lodgement 45 of any sparks or molten metal, and at the

same time by not interfering with the ordinary fastening device for the legging which is designed and intended to be removed by a single continuous pull in one direction.

55 Referring now more particularly to the drawing, a legging 5 of the type adapted to be wrapt about the leg of a wearer with the outer edge overlapping the inner edge at one side of the wearer's leg, is provided with a metal stiffener 6 in the outer edge which is attached at the bottom of the legging by a rivet 7 or other suitable means. The inner portion of the legging is provided at the bottom with a strap 8 attached thereto by rivets 9 which form pockets into which a lower spaced extremity 10 of the metal stiffener 6 is inserted for varying the size of the legging at the bottom. Extending from the front of the legging is a covering vamp 11.

60 At the top of the legging is a metal plate 12 attached by rivets 13 and having a number of adjustment slots or openings 14 adapted to be engaged by a metal hook 15 having a 65 projecting tongue 16 for engaging in any one of the perforations 14 and preferably being attached to the over-lapping edge by inserting it through perforations in the legging and in the stiffening strip 6. To the outer free end of the metal hook 15 is attached a 70 thong or strap 17 preferably of fabric, leather, or some non-fusing material, usually 75 leather of which the legging itself is preferably made.

80 The upper edge of the legging is cut and gathered at intervals by means of staples 18 which make it more nearly form fitting and the inner edge has a tab 19 for grasping and applying the legging, and at the side of the legging where it overlaps and is adjustably 85 attached at the top is a flap 20 which is secured to or formed integral with the remainder of the legging, and is adapted to fold 90 downwardly over the upper end of the overlapping edge and to cover the fastening plate 95 12 and the fastening hook 15 so that when the legging is applied the fastening parts are not even visible. The removing strap 17 depends below the edge of the flaps 20 so that 100 it may be grasped whether the flap is in place

or not and by raising and pulling on the strap the flap is raised and the hook is disengaged with a single movement which also disengages the lower fastening means for the 5 legging.

With this construction the upper fastening parts will be protected from any molten particles, the fastening means itself will be prevented from accidental catching or disengagement, the flap will cover the upper overlapping edge and tend to hold it in place, and the legging will present a neat and dressy appearance at the top. It should be understood that any type of quick removable fastening can be employed at the bottom of the legging and any fastening of the quick detachable type may be included at the top.

What I claim is:

1. A pull-off legging of the quick detachable type having metal fastenings at the top for securing the overlapping parts together, and a flap secured to the underlying part of the legging and extending over the top of the overlying legging part and covering the metal fastening parts to protect them from lodgement of molten particles.
2. In a legging of the quick detachable, overlapping type, having a releasable engaging member at the top with a depending non-metallic strap for disengaging the fastening means, and a flap extending from the top of the legging over the overlapping edge and being loose at its lower edge and covering the fastening means but not covering the depending end of the releasing strap.

SAMUEL N. SAGER.
